GRAIN-SORTING MACHINE

Frédéric Bertrand Bloc, Dijon, France, assignor
to Societe de Anciens, Etablissements Lhuillier,
Dijon, France, a corporation

Application October 13, 1936, Serial No. 105,423
In France October 30, 1935

1 Claim. (Cl. 209—95)

Apparatus for the sorting of grains is already known, in which the grains to be sorted are supplied to a rotating cylinder which is horizontal or slightly inclined and whose wall is provided with recesses of suitable size.

During the operation, a part of the grain will be caught in the recesses near the lower generatrix of the cylinder, and then, due to the rotation of the cylinder itself, the grains are carried around in the recesses and will only drop out after having been raised a certain distance.

When the grains are round or short, their position in the recesses is relatively stable, so that they will only fall after having been raised to a considerable height. A suitably placed trough collects these round grains, which are thus separated from the others.

The long grains contained in the recesses have a position which is not nearly as well assured, and they will drop almost at once, and at all events before they reach the level of the trough.

Due to the inclination of the sorting apparatus, or any other arrangement, the grains travel from one end to the other upon the lower part of the wall of the cylinder, and when they reach the point of discharge, they are considered as having been freed from the round grains.

It is shown by experience that in such known sorting devices, the grains rest upon the lower generatrix of the cylinder wall and form a sheet of greater or less thickness, and during the rotation this sheet will have a higher position according to the speed. In this sheet, a certain part of the grains will come several times in contact with the recessed wall, and it may happen that other grains reach the outlet of the cylinder without ever having been in contact with the recessed wall. Thus the sorting is not carried out upon these last-mentioned grains, which are still mixed with the round grains.

This action is the more evident, and hence the sorting is the more incomplete, according as the sorting apparatus is more heavily loaded with grain.

It has been proposed to obviate this serious drawback by means of devices adapted to modify the form and the arrangement of the sheet of grains, but such devices, owing to this severe work, are subject to rapid wear, and after a time they fail to give satisfaction.

The sorting machine in conformity with the invention is a considerable improvement with reference to the known machines. The thick sheet of grains whose inconvenience has been pointed out, is no longer formed, and thus all of the grains, without exception, come in contact with the recessed wall.

On the other hand, all of the grains will remain in the sorting machine for the same time and will travel over the same path, so that the

operation can be completely performed with the minimum loss of power and hence with the maximum yield.

In accordance with the invention, each sorting machine, or section of such machine, comprises a recessed cylinder. In the interior of said cylinder, and upon its whole length, is mounted a distributor for feeding the grains, in such way that the grains will drop into the cylinder simultaneously upon the whole length of this latter.

In addition to the usual trough which serves to collect the round or short grains, the invention employs, at a lower level, a trough which is located in such manner as to receive the long grains.

By this arrangement, the grains, of whatever kind, can only leave the sorting machine after they have been collected in one or the other of the troughs and thus the sorting machine has the maximum efficiency that can be obtained with the use of recesses.

As this efficiency is not absolute, and as the long grains, when dropping into the lower trough, may bring with them a certain number of the round grains, the invention further relates to a sorting machine made in several successive sections, each of which is arranged as above described, and the long grains which are collected by the trough of the first section and are still mixed with round or short grains, are delivered to a ring containing buckets, which raises them and pours them into the distributor of the second section, and so on, and finally the long grains issuing from the last section are freed from the round or short grains.

The invention is shown by way of example in the accompanying drawings.

Fig. 1 is a cross-section of one of the sections of a sorting machine according to the invention.

Fig. 2 is a longitudinal section of the above-mentioned section, on a line passing through the distributor.

Fig. 3 is a longitudinal section of one of the sections of the machine, on a line passing through the troughs receiving the long grains and the round grains.

Fig. 4 is a cross-section of a bucket-ring connecting two consecutive sections of the sorting machine.

Figs. 5 and 6 show modified forms of distributors.

Fig. 7 shows a modified form of the bucket-ring.

In the form of construction shown in Figs. 1 to 4, the sorting machine consists of a certain number of sections, that is, of unit cylinders such as 10, whose internal wall is provided as usual with recesses 11. The said sections are placed end to end, and form a continuous cylinder whose

axis is horizontal and which is supported by the frame 12 and rotated by means of rollers 13. In the interior of the sections and at a relatively high level, is mounted in the known manner a trough 14 adapted to collect the round or short grains falling from the recesses. At the bottom of said trough is located a conveyor 15, for instance of the screw type, which is driven by a pulley 16 and discharges in a continuous manner, to the exterior, the round grains which are collected.

In conformity with the invention, each section of the sorting machine contains a feeding distributor comprising a horizontal trough 17 and a screw conveyor 18 which is rotated by a pulley 19 and distributes the grain throughout the whole length of the trough.

The bottom of the trough is pierced with holes through which the grains may fall, but below this bottom is located a draw-plate 20, suitably guided, which is also pierced with holes and is operated from the exterior by a handle 21.

According as the holes in the draw-plate coincide more or less with the holes in the trough 17, the discharge of the grains which are distributed will be greater or less. In any case, the grains fall simultaneously throughout the whole length of the section.

In order that the grains shall not be thrown aside when thus meeting the wall, there is mounted upon the whole length of the section a deflector 22 whose lower part 23 has the form of a circular arc and is parallel to the wall 10.

The space between the part 23 and the wall 10 is very small, and corresponds practically to the thickness of a grain, and thus the grains falling from the distributor 17-20 are held against the recessed wall in a thin sheet, in which the grains are simply juxtaposed, substantially in a single layer.

At a short distance above the lower generatrix of the cylinder is located a trough 24 containing a screw conveyor 25. At the end of the section, the said conveyor enters a ring provided with buckets 26, Fig. 4. In this way, the trough 24 is interrupted at a point adjacent the said ring, but it continues in the following section.

As shown in Fig. 4, adjacent the said ring 26, only the shaft 29 of the screw appears. On the other hand, the trough 14 for the round grains consists of a sleeve 27 entirely surrounding the conveyor 15. As to the distributing trough 17, one of its wings is suitably extended at 28 so as to collect the grains falling from the buckets.

The operation of a sorting machine of this construction is as follows.

The grains which are brought to the trough 17 of the first section are distributed by the conveyor 18 over the whole length of this section, and fall in the interior of the cylinder, passing through those holes in the trough 17 which are uncovered by the draw-plate 20.

The grains received by the deflector 22 are placed in a thin sheet upon the recessed surface 10 by the part 23 of this deflector.

The grains, which are more or less engaged in the recesses according to their shape and size, are brought along by the rotation of the wall 10, but at the end of a certain movement, the long grains, which have but little stability in the recesses, will drop into the trough 24 and are then taken up by the conveyor 25.

The round or short grains remain in the recesses and will only leave them by the action of

gravity, at a much greater height. After having passed above the level of the trough 14, these round or short grains are carried by the conveyor 15 and are discharged from the sorting machine. 5

Obviously, the level of the trough 14 can be adjusted to a greater or less height when in operation, in order to provide for a sorting which is best adapted for the grain to be sorted.

The long grains which may still be mixed with some round or short grains, are brought by the conveyor 25 to the end of the section, and from there, they fall into the ring of buckets 26 which collects and raises them and then pours them into the distributing trough 17 of the next section. 15

It will be noted in general, that in the sorting machines with recesses, the more the long grains contain round grains, the less the round grains raised by the recesses will contain long grains lost in their mass. 20

In the present case, the first section of the sorting machine removes the greater part of the round grains from the mixture, and in order to reduce the percentage of long grains thus improperly situated, it is preferable to provide the second section with smaller recesses than those used in the first section, and so on for the successive sections, and thus the sorting machine will afford a better yield, both qualitative and quantitative, than the known sorting machines. 30

The invention is not limited to a particular form of construction of the sorting machine, and this may obviously comprise but a single section, in which case the bucket rings may be eliminated.

The type of feeding distributor can also be varied without exceeding the limits of the invention. For instance, instead of a draw-plate as shown in Figs. 1 and 2, it may be provided with valves 30 with spring or counterweight, as shown in Fig. 5, or it may be accompanied by grooved rollers 31, as shown in Fig. 6.

Any device for discharging the grains in thin and regular sheets may be adopted.

As concerns the bucket ring, it is also evident that the invention is not limited to the embodiment herein described in which the said ring has the same diameter as the recessed wall.

As shown in Fig. 7, it is possible to use a ring such as 32 having a smaller diameter than the wall 10 and rotating on an axis 33 with an independent movement.

It is understood that other forms of construction may be adopted for all of the parts comprised in the sorting machine.

I claim:

A grain sorting machine comprising, in combination, a horizontal and continuous rotary cylinder with recesses in its inner wall, means for feeding and distributing the grain continuously over the whole length of the cylinder, means located in the upper part of the interior of the cylinder and extending horizontally throughout the length of the cylinder to catch short grains, and a horizontally extending trough located in the lower part of the interior of the cylinder and having a horizontal collecting edge spaced from the interior of the cylinder a distance sufficient to permit the long grains to be carried above the same and extending slightly above the bottom generator of the cylinder to catch the long grains which are too large to remain in the recesses of the cylinder when the same are carried above said trough. 60
